LOADING PLATE FOR TOWEL DISPENSERS

Joseph L. Zizzi, Utica, N.Y., assignor to Joseph Darman, Utica, N.Y.

Filed July 20, 1954, Ser. No. 444,423

5 Claims. (Cl. 312—38)

This invention relates generally to continuous roll towel dispensers and has for its primary object the provision of an improved construction embodying a smoothing plate mechanism and operating means therefor effective to automatically properly position the smoothing plate upon actuation of the dispensing mechanism.

Another object of this invention is to provide improvements in a dispensing assembly which will render the same more readily and rapidly serviceable in the operation of loading the mechanism with a fresh supply of toweling.

Still another object of this invention is to provide an improved smoothing assembly for towel dispensers which includes a fixed smoothing plate and a hinged smoothing plate cooperable therewith to effectively smooth soiled toweling as the same passes therebetween for disposition on a take-up roll.

Another object of this invention resides in the provision of an improved smoothing mechanism in conformity with the foregoing object wherein the fixed smoothing plate is provided with an offset portion providing a groove within which the free edge of the hinged smoothing plate is received for effectively tensioning a substantially large area of toweling to enhance the smoothing operation performed thereon.

A still further object of this invention is to provide an improved smoothing mechanism for towel dispensers wherein a hinged smoothing plate is movable toward and away from a fixed smoothing plate so as to permit the passage of a person's hand between the smoothing plates when the dispensing mechanism is being loaded with a fresh supply of toweling and wherein linkage means joins the abrasive rolls forming a portion of the dispensing unit with the hinged smoothing plate such that a towel dispensing operation subsequent to loading of the unit will automatically return the hinged smoothing plate to its proper and operative position in close proximity to the fixed smoothing plate.

Another object of this invention is to utilize a smoothing mechanism having a fixed smoothing plate and a movable smoothing plate wherein the movable smoothing plate is normally spring urged into engagement with the fixed plate and wherein the spring mechanism is of such nature as to effect an even pressure throughout the area of contact between the fixed and movable plates to insure an even smoothing action across the area of the toweling and assure a proper take-up action of the toweling on an associated take-up spindle.

Still another object of this invention is to provide an improved smoothing mechanism in conformity with the foregoing object wherein the linkage means includes a bell crank member movable with the hinged smoothing plate between its operative and loading position and wherein a spring mechanism is novelly associated with the bell crank member to permit the same to be positioned only in the two aforementioned positions, both positions being so related as to the force applied by the spring mechanism with respect to the pivot point of the

2

bell crank that the force of the spring is over-center of the bell crank pivot axis one way or the other in the two corresponding positions.

A further object of this invention is to provide an improved smoothing plate operating mechanism in conformity with the foregoing objects wherein the linkage also includes a link member pivotally connected to one end of the bell crank and disposed at its opposite end in the path of movement of an abutment member carried by an abrasive roll, when the smoothing plate is in the inoperative position, such that actuation of the abrasive roll and consequent engagement of the abutment member against the one end of the link will reverse the over-center relationship of the spring with respect to the bell crank such that the spring may continue the motion of the bell crank and consequently the hinged smoothing plate to the position wherein the hinged smoothing plate is in close proximity to the fixed smoothing plate.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the improved dispensing unit;

Figure 2 is an exploded perspective view showing the fixed and hinged smoothing plates;

Figure 3 is a vertical section taken through the dispensing cabinet showing the dispensing unit operatively positioned therein and further showing the smoothing plate actuating mechanism;

Figure 4 is an enlarged sectional view showing the operative relationship between the fixed and hinged smoothing plates;

Figure 5 is a perspective view of a portion of the dispensing unit showing details of the fixed and hinged smoothing plates and the actuating mechanism on an enlarged scale;

Figure 6 is an enlarged vertical section taken substantially along the plane of section line 6—6 in Figure 3; and

Figure 7 is an enlarged sectional view showing details of the smoothing plates.

Referring now more particularly to the drawings, and more specifically at this time to Figure 1 thereof, wherein the dispensing unit is shown, the unit will be seen to consist of a pair of side plate members 10 and 12 which rotatably carry therebetween a pair of abrasive roll members 14 and 16. The side plates 10 and 12 are rigidly interconnected at three spaced points by means of the upper rear mounting bar member 18 whose opposite threaded end 20 projects through apertures in the side wall and receives nut member 22 thereon, by means of a fixed loading plate member 24 at the rear of the assembly and below the mounting bar 18 and at the forward portion thereof by means of a transverse support bar member to which the arcuate protector plate 26 is rigidly secured. The support rod or bar, like the mounting bar 18, is provided with opposite threaded ends 28 which project through suitable apertures in the side walls 10 and 12 and which are provided thereon with nut members 30 for effectively completing their fastening thereto.

As seen most clearly in Figures 2 and 4, the rigidifying connection effected by the fixed smoothing plate 24 is due to the provision of the laterally bent ears 32 and 34 disposed at opposite ends thereof, both of which are apertured and are adapted to engage against the inner surfaces of the side plates 10 and 12 and receive fastening elements 36 therethrough to securely interconnect the side walls 10 and 12.

To prevent movement of the fixed plate 24 about the fasteners 36 as a pivot, the upper or rearwardly inclined portion 38 thereof is provided at its opposite ends with the laterally projecting hook members 40 and 42 which are adapted to engage about stud members 44 which extend through and are fixed to the side walls 10 and 12.

Thus, it will be seen that the fixed mounting plate, the mounting rod or bar and the support rod or bar effectively and rigidly interconnect the side plate members 10 and 12 such that these members are properly related one to the other to permit proper and effective mounting of the roll members 14 and 16.

As seen most clearly in Figure 3, the dispensing unit shown in Figure 1 is mounted within a cabinet assembly indicated generally by the reference character 46 and it is to be noted that the cabinet in cooperation with the dispensing unit presents a continuous loop of toweling such as is well known in the art, the clean toweling end of the continuous loop being indicated by the reference character 48 and the soiled end of the continuous loop being indicated by the reference character 50. That is, as is conventional, the clean portion of the toweling issues from adjacent the front of the cabinet, the front door thereof being indicated generally by the reference character 52, and the soiled portion of the continuous loop projects upwardly into the bottom of the cabinet adjacent the rear portion thereof as will be readily apparent from Figure 3.

Although the details of the dispensing assembly per se forms no part of this invention, it is necessary to realize that the two roll members 14 and 16 are operatively interconnected by the provision of sprocket members 54 and 56 on one free end of their journal shaft with these sprockets being drivingly associated by the provision of a flexible chain member 58 therearound as will be seen most clearly in Figure 1. Thus, as the clean toweling portion 48 is pulled from the cabinet by a user, the roll member 16 will be rotated in a well known manner to impart a similar rotative motion to the roll 14 such that the soiled toweling will be rolled up on the spindle member 60 as the roll 14 is rotated. It will be further realized that the dispensing mechanism also includes a cam member 62 mounted on the journal shaft 64 for the roll 16 at the end opposite from the sprocket 56 and that this cam member 62 includes a rigid abutment member 65 integral therewith and adapted to be rotated as the roll 16 is rotated. Although the cam member 62 is of no moment insofar as the subject matter claimed herein is concerned, the abutment member 65 forms an important part of this invention.

Referring now more particularly to Figures 1, 2 and 4, it will be seen that a movable smoothing plate indicated generally by the reference character 66 is hingedly mounted between the side wall members 10 and 12 adjacent the lower rear corner portion thereof and in this respect it will be noted that the movable smoothing plate 66 embodies a main body portion 68 provided at opposite lower corners thereof with the hinge roll members 70 and 72 which rotatably receive the inner end of hinge pin members 74 which are threadedly engaged through the side walls 10 and 12 for effecting the pivotal connection between the smoothing plate 66 and the side walls.

The smoothing plate 66 will further be seen to consist of a free edge portion 76 angulated with respect to the main body portion 68 thereof and in this respect it is to be noted that the angulation between the portion 76 and the portion 68 is such as to permit the portion 76 to be disposed substantially horizontally when the smoothing plate 66 is in operative position, as shown most clearly in Figure 4. In conjunction therewith, the rearwardly inclined portion 38 of the fixed smoothing plate 24 is joined to the lower or vertical portion 78 of the fixed plate by means of a forwardly inclined portion 80

so that the portions 38 and 80 provide and present a groove or trough therebetween into which the reversely bent free edge portion 82 of the movable plate is projected when in the operative position. To prevent actual engagement of the edge 82 against the portion 80 of the fixed plate, spacer tabs 84 are provided on the fixed plate portion 80 to prevent positive engagement of the edge 82 therewith. The effect of this construction is to slightly space the free edge of the movable smoothing plate from the forwardly inclined portion 80 of the fixed smoothing plate and to obviate excessive frictional contact of the smoothing plate with the soiled toweling portion 50 as the same passes upwardly between the smoothing plate members onto the take-up spindle 60.

15 The above described structural configuration of the fixed smoothing plate and the cooperative relationship of the hinged plate therewith effects an improved smoothing action on the toweling being fed onto the take-up roll 60 by virtue of the fact that the smoothing action 20 on the soiled toweling not only takes place in the region immediately between the free edge 82 and the portion 80 but also throughout the entire extent of the rearwardly inclined portion 38 of the fixed plate member and partially around the smoothly beaded upper edge portion 25 86 thereof. Thus, there is provided more than the usual line contact between the smoothing plate members and the soiled toweling and the consequent line smoothing action thereon and it will be readily apparent that an improved smoothing action takes place as a result thereof 30 since the smoothing action occurs over a substantially large area of the toweling.

Disposed adjacent the rear edge and on the outer side of the wall member 12 is a bell crank member 88 provided with a pivot pin member 90 projecting through an intermediate portion thereof and through the side wall 12 such that the bell crank is pivotally attached to the side wall so as to be movable between the full and dotted line positions shown in Figure 3. The lower end of the bell crank is provided with a relatively narrow projecting portion 92 which terminates in a laterally bent finger portion 94 which projects through an elongated arcuate slot 96 in the side wall 12 to be disposed behind the movable smoothing plate 66 in the manner shown most clearly in Figure 5. The portion 68 of the plate 45 66 is notched as at 98 in the region of the free end of the finger 94 and on the forward surface thereof is rigidly attached a tab member 100 having an angularly offset portion 102 against which the finger 94 engages. The purpose of the tab 100 is to present a substantially 50 vertical space or surface engaged by the finger 94 so that the finger 94, being spring urged into engagement with the tab 100 as will be presently apparent, will exert the most effective force to the plate 66 for urging the same into smoothing contact with the fixed plate assembly 24. 55 Pivottally secured as by pins 104 to the upper end of the bell crank 88 is a substantially horizontally disposed link member 106 whose opposite free end terminates in a laterally projecting ear 108 which extends through a horizontally elongated slot 110 in the side wall 12. The 60 ear 108 is wider than the remaining portion of the link and the slot 110 such that the portion 112 thereof is disposed closely adjacent the inner surface of the side wall 12 to impart a guiding action to this end of the link.

The end of the link 106 which is pivotally attached to 65 the bell crank 88 has an enlarged cam portion 114 which extends beyond the corresponding end of the bell crank 88 and against which the free end of a resilient spring finger member 116 is adapted to engage. The spring finger is rigidly attached to the laterally projecting leg 118 70 of an L-shaped bracket member 120 whose other leg is rigidly affixed to the outer surface of the side wall 12 as by fasteners 122, the connection between the spring finger 116 and the bracket leg 118 being effected by any suitable fastening means such as the member 124 as illustrated in Figure 3. The spring finger 116 is so disposed

with respect to the cam portion 114 of link 106 and the bell crank 88 that when the bell crank is disposed in either one of its opposite limits of position as indicated by the full and dotted lines in Figure 3, the spring finger will exert a force on the bell crank 88 through its pivot pin 104 to maintain the bell crank in the position to which it has been moved.

The purpose and operation of the link and bell crank system is such as to return the removable smoothing plate 66 to its operative position whenever the movable smoothing plate is disposed in its inoperative position such as that in dotted lines in Figure 3 to permit loading of the dispensing assembly. That is, it will be clear that upon servicing of the cabinet to introduce a fresh supply of toweling therein, an operator passes his hand upwardly through the rearward bottom opening of the cabinet to swing the plate 66 away from the fixed plate 24 to permit the fresh supply of toweling to be wound once or twice around the takeup spool 60. It is not then necessary for the operator to then swing the smoothing plate 66 back into its operative position inasmuch as pulling upon the clean towel loop portion 48 which hangs from the cabinet will rotate the roll members 14 and 16 and will consequently rotate the abutment member 65. Since the bell crank and link 88 and 106, respectively, are disposed in the full line position shown in Figure 3, the ear 108 will be disposed in the path of movement of the abutment member 66 and will be struck thereby to move the link 106 a sufficient distance to reverse the over-center relationship of the spring 116 against the cam portion 114 of the link 106 whereby the resiliency of the spring member will continue pivoting the bell crank in a corresponding direction until the finger 94 has returned the smoothing plate 66 to its operative position.

Thus, it will be readily apparent that it will be impossible for the movable smoothing plate 66 to be left in its inoperative position.

A further improvement which is effected in the loading or smoothing plate mechanism resides in the mechanism mounted on wall 10 which equalizes the pressure against the movable smoothing plate 66. This mechanism takes the form of an auxiliary bell crank 88' pivotally mounted on the side wall 10 by means of the pivot pin 90' and which is provided with a relatively narrow lower end projection 92' similar to the previously mentioned bell crank 88. Similar also to bell crank 88, the auxiliary bell crank has its lower extremity provided with a laterally bent finger portion 94' projecting through an arcuate slot 96' in side wall 10, this finger portion being adapted, in cooperation with a spring mechanism later described, to urge the hinged smoothing plate 66 toward and into engagement with the fixed plate 24.

To this end, it is to be noted that both ends of the plate 66 are notched as previously noted with respect to notch 98 and the finger portion 94' of the auxiliary bell crank projects into that notch adjacent the side wall 10 and into engagement with the tab member 100', or more specifically, into contact with the angularly offset portion 102' of this tab. Tab 100', like the previously described tab 100, is securely attached to the plate 66.

The spring mechanism which is associated with the auxiliary bell crank 88' is similar to the one associated with bell crank 88 in that it employs an L-shaped bracket member 120' secured to side wall 10 by fasteners 122' upon which the spring finger 116' is mounted. The free end of the spring finger bears against the upper end of the auxiliary bell crank and maintains the same to one or the other side of center corresponding to the open and closed positions of the loading or movable smoothing plate. In the same way that the spring finger 116 acts upon the enlarged end 114 of link 106 to urge bell crank 88 into either one of its two positions, the spring finger 116' acts directly upon the upper end of auxiliary bell crank 88'. Since the dimensions of the two bell cranks 88 and 88' are similar, substantially the same leverage is

exerted upon the smoothing plate 66 by these two bell cranks such that the toweling is frictionally engaged thereby with a uniform force all along the line of contact with the beaded edge 82 of the loading plate.

To reverse the over center relationship of the auxiliary bell crank 88' as the loading plate is moved from its open position toward the closed position, means is provided to impart the necessary movement to the auxiliary bell crank. This means takes the form of a retaining bracket having one portion 126 secured to the loading plate and an opposite end portion 128 overlying the finger 94' in spaced relation to tab 100'. Thus, as the loading plate is moved, by the mechanism previously described, toward the closed position, the bracket portion 128 engages finger 94' and imparts a corresponding movement to auxiliary bell crank 88'.

It is extremely important that the auxiliary bell crank be utilized in conjunction with the primary or main bell crank inasmuch as the uniformity in pressure exerted upon the soiled toweling as attained thereby assures that the soiled toweling will be evenly rolled upon the take-up spindle 60. Any unevenness in tension against the toweling will cause the toweling to shift laterally toward the area of lesser tension and wind unevenly upon the take-up spindle.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

35. What is claimed as new is as follows:

1. In a towel dispensing assembly, a pair of spaced, rigidly interconnected side wall members, a fixed smoothing plate rigidly secured between said side wall members, a movable smoothing plate hingedly secured between said side walls, the hinge point of said movable plate being spaced from the fixed plate such that the movable plate is swingable between one position away from the fixed plate to permit the passage of toweling therebetween during loading operation of the assembly and a second position wherein a free edge portion holds a portion of toweling against the fixed plate, a bell crank pivotally secured intermediate its ends to one of said side walls and having one end abutting said movable plate, a spring member engaging the opposite end of said bell crank urging said crank between limits of pivotal movement on said one side wall, a pair of abrasive rolls journaled between said side walls, an abutment member rigidly secured to one of said rolls for rotation therewith, and link means engaged by said abutment member and connected to said bell crank urging the latter on its pivot to a position over-center with relation to said spring, said spring being operable to move the bell crank into engagement with the movable smoothing plate against the fixed plate.

2. In a towel dispensing assembly as set forth in claim 1 wherein an auxiliary bell crank is pivoted intermediate its ends to the other of said side walls and having one of its ends abutting said movable plate, and a second spring member engaging the opposite end of said auxiliary bell crank between limits of pivotal movement of said other side wall, the spring members cooperating to effect an even pressure along the length of the movable plate relative to the fixed plate.

3. In a towel dispensing assembly, a pair of spaced, rigidly interconnected side walls, an abrasive roll journaled between said side walls and having an abutment member rigid therewith adjacent one of the side walls, said one side wall having an opening adjacent said roll, a bell crank pivoted intermediate its ends to said one side wall, a link pivotally connected to one end of said bell

crank and extending therefrom toward said side wall opening and terminating in a laterally projecting ear extending through the opening, said bell crank being swingable to move said ear into and out of the path of movement of said abutment member, a resilient spring element fixed to said one side wall and engaging the link adjacent its pivotal connection with the crank such that the crank is normally urged into one of limits of swinging movement, said one side having an elongated slot therein adjacent the other end of said bell crank, a laterally projecting finger on said other end of the bell crank through which said finger projects, a smoothing plate hingedly secured between said side walls and engaged by said finger such that said link when in the path of movement of the abutment member will be urged by the same to move the bell crank into over-center relation with said spring whereby the spring will continue the motion of said bell crank and urge the smoothing plate to operating position.

4. In a towel dispensing assembly as set forth in claim 2 wherein an auxiliary bell crank is pivoted intermediate its ends to the other of said side walls and having one of its ends abutting said movable plate, and a second spring member engaging the opposite end of said auxiliary bell crank between limits of pivotal movement of said other side wall, the spring members cooperating to effect an even pressure along the length of the movable plate relative to the fixed plate.

5. In a towel dispensing assembly, a pair of spaced, rigidly interconnected side wall members, a fixed smoothing plate rigidly secured between said side wall members, a movable smoothing plate hingedly secured between said side walls, the hinge point of said movable plate being spaced from the fixed plate such that the

movable plate is swingable between one position away from the fixed plate to permit the passage of toweling therebetween during loading operation of the assembly and a position wherein its free edge holds a portion of toweling against the fixed plate, a bell crank pivotally secured intermediate its ends to one of said side walls and having one of its ends abutting said movable plate, a spring member engaging the opposite end of said bell crank urging said bell crank between limits of pivotal movement on said one side wall, a pair of abrasive rolls journaled between said side walls, an abutment member rigidly secured to one of said rolls for rotation therewith, and link means engaged by said abutment member and connected to said bell crank for urging the latter to a position over-center with relation to said spring, whereby the spring will move the bell crank to engage the movable smoothing plate against the fixed plate, an auxiliary bell crank pivoted intermediate its ends to the other of said side walls and having one of its ends abutting said movable plate, and a second spring member engaging the opposite end of said auxiliary bell crank urging said auxiliary bell crank between limits of pivotal movement on said other side wall, the first mentioned spring member and the second spring member cooperating to effect an even pressure along the edge of the movable smoothing plate against the fixed plate.
